CLAIM

The ornamental design for hook with clasp release, as shown and described.

DESCRIPTION

FIG. 1 is a top front perspective view of a hook with clasp release, showing my new design;

FIG. 2 is a top plan view thereof;

FIG. 3 is a bottom plan view thereof;

FIG. 4 is a right side elevation view thereof;

FIG. 5 is a left side elevation view thereof;

FIG. 6 is a front elevation view thereof; and,

FIG. 7 is a rear elevation view thereof.

The broken lines shown in the drawings depict environmental structure that forms no part of the claimed design.
